PLATE OR SIMILAR ARTICLE

A. Baker Barnhart, New York, N. Y., assignor to The Rosenthal-Block China Corporation, New York, N. Y.

Application March 12, 1957, Serial No. 45,210

Term of patent 7 years

(Cl. D44—15)

The figure is a plan view of a plate or similar article of conventional configuration, showing my new design.

I claim:

The ornamental design for a plate or similar article, as shown and described.
